PUMP

Bernard H. Scott, Glendale, Calif., assignor of
one-half to Amos W. Elliott, Los Angeles,
Calif.

Application July 18, 1936, Serial No. 91,299

5 Claims. (Cl. 103—179)

This invention relates to well pumps and specifically to the general type of pumps commonly employed in oil producing wells. The present application is a continuation-in-part of my copending application for Deep well pumps filed July 5 22, 1935, bearing Serial Number 32,554.

The recovery of oil from the great depths to which present day drilling methods are capable of reaching is in many instances impracticable 10 due to the excessive cost of the operation of pumping machinery. The sucker rod ring utilized in conventional types of pumping apparatus for control and operation of the plunger, is usually of a length substantially equal to the depth 15 of the producing oil sands. To offset the greater strain imposed upon the rods by their increased length in deeper wells, heavier materials must be employed in their manufacture, adding to the dead weight necessarily lifted on each alternate 20 stroke of the pump. This weight, combined with the proportionately greater unavoidable friction of the rod string on the walls of the tubing string, through which the fluid is pumped, is conveyed to the well surface, requires a power expenditure 25 which increases out of proportion to the extension of the rod string, imposing a definite limit on the depth at which wells may be profitably operated, regardless of the economy of the initial drilling methods employed.

30 It is a general object of my invention to provide a deep well pump adapted to utilize the weight of the sucker rod ring on its pumping stroke to raise a column of fluid in a tubing string, and to further employ the hydrostatic pressure 35 of the column of fluid pumped upwardly into the tubing to elevate the rod string in its opposite stroke, and thereby minimize the power required for its operation, as well as to obviate excessive strain on the sucker rods.

40 Another object is to provide a pumping assembly comprising a pair of plungers reciprocably suspended in a tubing by a sucker rod string, adapted to raise a fluid column in the tubing and to raise on alternate strokes the sucker rod string 45 by the hydrostatic pressure of the fluid pumped, which pumping assembly may be removed from the well without pulling the tubing, to facilitate cleaning and replacement of the parts thereof.

Another object is the provision of a deep well 50 pump embodying two or more plungers suspended by a string of sucker rods having a swivel connection between the plungers to obviate the necessity of relative concentric alignment of the plungers and rod string.

55 Another object is to provide a pump struc-

ture, of the character indicated, easily adaptable to compensate for variations in specific gravity of the fluid pumped, and in the depth of the well upon which the weight of the string of sucker rods and the fluid column carried by the tubing, 5 depend, by varying the cross sectional area of the plungers on which the hydrostatic pressure of the fluid column in the tubing is directed and thereby reduced to a minimum the power required by operation of the pump.

Still other objects will be apparent to those of skill in the art to which my invention appertains upon an examination of the following description, read in the light of the accompanying drawings, in which—

Fig. 1 is a diagrammatic section of my invention illustrating its operation on the upstroke of the sucker rods;

Fig. 2 is a view similar to Fig. 1 showing the operation on the downstroke of the rods;

Fig. 3 is a sectional view of the upper part of my invention suspended from sucker rods and tubing string.

Fig. 4 is a longitudinal sectional elevation, being a lower continuation of Fig. 3;

Fig. 5 is a section of the lower portion of the invention extending downwardly from the lower end of the portion of the pump shown in Fig. 4.

Referring to the drawings in detail, the numerals of which indicate similar parts throughout the several views, 10 designates a string of tubing extending to the top of a producing well through which it is desired to pump oil fluid from the sands immediately therebelow. A collar 11 is threaded to the lower end of tubing string 10 30 having an internal annular tapered seat 12. Supported on seat 12 is a hollow plug 13, on the upper end of which are formed a series of downwardly directed teeth 14 to facilitate removal by fishing means well known in the art upon fracture of the 40 rod string or other part thereabove.

A tubular jacket 15 is attached to the externally threaded lower end of plug 13, having a breather coupling 16 threaded to its bottom. The bore of plug 13, at its lower end, and the upper bore of 45 breather coupling 16 are recessed to corresponding diameters at 17 and 18, respectively. Between the oppositely disposed shoulders formed by said recesses, a pump liner 19 is clamped. A plunger jacket 20 of a diameter equal to that of 50 jacket 15 is connected to the lower end of coupling 16. A plunger liner 21 closely fitting the bore of jacket 20 is clamped between the lower end of coupling 16 and a jacket coupling 22, threaded to the lower end of jacket 20. Lateral 55

- ports 23 are provided in coupling 16, and the bore of said coupling is enlarged below ports 23 to a diameter substantially equal to that of plunger liner 21, for a purpose referred to below.
- 5 A connecting jacket 24 is similarly threaded below jacket coupling 22 and has attached to its lower end a lower breather coupling 25. Coupling 25 is provided with a recessed bore in its upper end to form a shoulder 26 on which a pump liner 10 27, of substantially the same diameter as that of liner 19, is supported. A fluid tight fit between jacket coupling 22 and the smaller diameter liner 27 is effected by bushing 28, clamped with the liner between coupling 22 and the lower breather 15 coupling 25. Lateral ports 29 in coupling 25 permit the free passage of fluid in the well therethrough in response to pressure differentials created by operation of the pump in the manner later described.
- 20 A lower plunger jacket 30 of a diameter equal to the diameter of jackets 20 and 24 is connected to coupling 25 having a sleeve 31 threaded to its lower end. A lower plunger liner 32 of substantially the same diameter as that of liner 21 is 25 clamped between the lower end of jacket coupling 22 and sleeve 31. At the end of the string and threaded to sleeve 31 is a guide bushing 33 having an inwardly tapered bottom to facilitate lowering of the pump in the tubing or into an open hole 30 below the tubing. The upper end of bushing 33 extends into sleeve 31 and has a reduced outside diameter. A valve seat 34 is clamped on the upper end of bushing 33 by cage 35 threaded on the upper reduced periphery of bushing 33. A 35 ball valve 36 in cage 35 is adapted for upward displacement to admit fluid from the well into the bore of sleeve 31.
- Referring again to Fig. 3, 37 indicates the lower end of the usual sucker rod string to which a 40 cage 38 is connected by a coupling 39. A lower plunger stem 40 slidably extending through plug 13, liner 19, and breather coupling 16 is hung from cage 38 by a hollow bushing 41, said cage freely communicating the bore of the lower 45 plunger stem 40 with the tubing above plug 13. A hollow plunger 42 of greater diameter than plunger stem 40 to enable the plunger to slidably engage the walls of liner 21 is connected to plunger stem 40 by coupling 43, the upper end of 50 plunger 42 forming an annular shoulder 44. The plunger is adapted to reciprocate under control of the sucker rod string between the limits of the reduced bore of breather coupling 16 and bushing 28.
- 55 In a recess machined in the lower bore of plunger 42 a peripheral flange 45 of a swivel sleeve 46 is held by swivel bushing 47 threaded into the plunger. The sleeve is thus free to rotate, being held against longitudinal movement with respect 60 to the rod string 37 by bushing 47. Sleeve 46 is of smaller diameter than plunger 42 to form a pump chamber 48 between the lower end of the plunger and bushing 28. A coupling 49 provided with lateral ports 50, communicating the bore 65 of the plunger with the bore of jacket coupling 22 above bushing 28 connects a hollow lower plunger stem 51 to sleeve 46. Stem 51 is of a diameter substantially equal to the diameter of stem 40 and forms a fluid tight fit with the walls 70 of liner 27. Extending below the lower breather coupling 25, stem 51 has attached to its lower end, by a coupling 52, a production plunger 53, diametrically larger than stem 51, which reciprocably engages the wall of liner 32. The difference in 75 outside cross sectional area of stem 51, coupling
- 52 and plunger 53 forms an upwardly directed shoulder 54, hereinafter referred to.
- A blind cage sleeve 55 is secured to the lower end of plunger 53 by a bushing 56. Integrally formed with bushing 56 and extending downwardly into sleeve 55 is an abutment 57 to limit upward movement of a ball valve 58 and permit the passage of fluid upwardly therearound. Valve seat 59, clamped between an annular shoulder 60 formed in sleeve 55 and a lower bushing 61 10 threaded into said sleeve, normally supports ball valve 58 so as to close the bore of plunger 53 to pressure thereabove.
- A tubing section 62 is threaded into collar 11 and extends downwardly to any depth desired to 15 protect the pump liners and jackets, particularly where the pump is employed in an open hole.
- It will be noted that the entire pump assembly, including liners and jackets, is supported on the tapered seat 12, permitting its removal from the 20 well for cleaning, replacement of worn parts, and repair, without pulling the tubing string, as will be obvious to those of skill in the art to which this invention appertains.
- The operation of my invention is briefly described as follows: On the downstroke of the sucker rods which lowers the plunger stems 40 and 51 and plungers 42 and 53, fluid trapped below plunger 53 by the closure of valve 36 displaces valve 58 and passes upwardly through the 30 hollow string, entering the tubing string above plug 13 through cage 38. Thus a column of fluid substantially equal to the cross-sectional area of the lower plunger multiplied by the length of the stroke will, in normal operations (with the 35 tubing full of oil fluid) be discharged at the top of the well.
- At the conclusion of the downstroke valve 58 will close due to the greater hydrostatic pressure of fluid in the tubing over the pressure in the 40 well below valves 36 and 58. As the sucker rods are lifted, valve 36 will be raised and fluid admitted below plunger 53 for the next downward stroke thereof. With valve 58 closed on the upstroke, the hydrostatic pressure of the fluid in 45 the tubing multiplied by the cross-sectional area of the upper plunger minus, substantially, the hydrostatic pressure at the base of the column of fluid in the tubing times the cross-sectional area of the plunger stem 40 will be conveyed through 50 cage 35, plunger stem 40, and ports 50, for exertion upwardly against plunger 42 to alleviate the weight of the sucker rods, plungers, etc.
- In addition to the pressure exerted against the lower end of plunger 40, the upward lift of the 55 rods will be facilitated by the pressure of the fluid in the well against the lower plunger through valve 36. This upward pressure by fluid in the well will be partially offset by well fluid under pressure entering ports 23 and 29 in breather couplings 16 and 25 which exerts downward pressure on the annular shoulders 44 and 54 on the upper end of each plunger formed by the increased diametric dimensions of the plungers over 60 that of the plunger stems.
- The balance of pressure upwardly to raise the 65 pump plungers may be increased by increasing the diameter of the plungers relative to cross-sectional area of the tubing, or by adding to the number of plungers against which hydrostatic pressure of the fluid may be directed.
- On the upstroke of the upper plunger 42 the fluid level in the tubing will be lowered by a column equal to the cross-sectional area of the shoulder 54 times the length of the stroke. When 70

the sucker rods are again lowered, this fluid from above bushing 28 will be replaced in the tubing and the level again raised by the downward movement of the upper plunger relative to the bushing, as clearly shown in Fig. 2.

It will be apparent that the amount of reduction in weight of and carried by the sucker rods on the upstroke of the plunger by the utilization of the fluid in the tubing string, in the manner above described, will depend primarily upon the pressure in the well, the cross-sectional dimensions of the plunger and stems, individually, and with respect to each other, specific gravity of the fluid pumped, the diameter of the tubing, and the depth of the well. It is believed, however, that changes in structure of particular embodiments to compensate for variances in the other factors above mentioned to obtain maximum efficiency of my invention is well within the ability of those of skill in the art.

It should be noted, however, that the comparative lengths and weights of the sucker rod strings in wells of various depths will, in a large measure, be compensated for by corresponding variances in the length of the column of fluid in the tubing and in its hydrostatic pressure exerted to raise the upper plunger.

While the pump of my invention is adapted, as described and illustrated, to withdrawal from the well without disturbing the tubing due to the support of the liners and jackets on the tapered seat 12 of collar 11, no locking means, required in many conventional type insert pumps, is needed, as the hydrostatic pressure in the tubing above collar 11 exerted on plug 13 will resist any tendency of upward movement of the plungers toward displacement of the plug and liners as will be obvious to those of skill in this art.

It will be understood that numerous other changes such as in the type of valves employed, relative length, design, and arrangement of the parts, may be embodied in modifications hereof, to conform to specific requirements, without departing from the spirit of my invention.

45 What I claim and desire to secure by Letters Patent is:

1. A pump comprising a tubular member, a pair of plungers reciprocably disposed within said tubular member, and swivel means to connect said plungers comprising telescoping tubular members carrying relatively engageable flanges of substantially equal outside diameter, said last-mentioned tubular members being rotatable with respect to each other, and means closing the first-named tubular member above and below the uppermost plunger.

2. In a pump, a tubing string, a pair of pump barrels carried by said tubing in spaced relation, a pair of plunger liners carried by respective barrels, a plunger in each of said liners adapted to slidably engage the walls thereof, means connected to said plungers to reciprocate the same in unison, means to communicate one of the lin-

ers below the plunger therein with the tubing, a breather communication between the last mentioned liner above the plunger therein with the area outside of said tubing and liner, means to communicate the other of said liners on one side 5 of the plunger therein with the tubing on alternate strokes of the last mentioned plunger, and a pipe carried by said tubing encircling said liners and communicated with the well.

3. A pump comprising a tubing string, a sucker rod string within said tubing string, a plunger carried by said rod string, a second plunger, a swivel connecting said plungers comprising a tubular member connected to one of said plungers and a second tubular member telescoping the 15 first tubular member and means connected to said members to substantially maintain the spaced relation of said plunger, said tubular members being rotatable with respect to each other.

4. In a pump, a tubing string, a sucker rod 20 string within said tubing string, a hollow stem connected to the lower end of said sucker rod string, a barrel carried by said tubing, a plunger carried by said stem in said barrel, a plug for the annular area between said stem and said 25 tubing above said plunger comprising a pipe having a hollow block connected in each of its ends, a jacket clamped between said blocks through which said pipe reciprocably extends, means to communicate said stem with the zone above said 30 plug, means to communicate the zone between said plug and plunger with the area around said tubing, a second plug for the area between said hollow stem below said plunger and the tubing, means to communicate the stem with the zone 35 between said plunger and lower plug, a second working barrel carried by said tubing below said first barrel, a second hollow plunger connected to said stem below said second plug and within said second barrel, and means to communicate 40 the zone between said second plunger and said second plug with the area around said tubing.

5. In a pump, a tubing string, a sucker rod string within said tubing string, a working barrel carried by said tubing, an upper plunger within 45 said working barrel, a hollow stem connecting said plunger with said sucker rod string, a second working barrel carried by said tubing, a second plunger within said second working barrel, a lower stem connecting said second plunger to 50 said upper plunger, closure means for the area between said hollow stem and said tubing string, a pair of spaced plugs for the area between the lower stem and the tubing string, said plugs being disposed adjacent respective working barrels, 55 means to communicate the area between said closure means and said upper plunger, and the area between said lower plunger and the adjacent plug with the area around the tubing string, and means to communicate said upper plunger with the area 60 in said tubing string around said lower stem and above said plugs.

BERNARD H. SCOTT.
